GASEOUS DISCHARGE TUBE MOTOR
CIRCUITWilliam G. Gorton, Belmont, Mass., assignor, by
mesne assignments, to Submarine Signal Com-
pany, Boston, Mass., a corporation of Delaware

Application November 20, 1943, Serial No. 511,159

2 Claims. (Cl. 318—345)

1

The present invention relates to an electrical control circuit for a variable speed drive and in particular it may be applied to a training control system for training any rotatable gear such as may be used in submarine signaling apparatus, in the training of Radar apparatus, in turret or gun training or in such similar devices. Such systems may also be incorporated in the follow-up device in such a manner that the gear being trained will follow the training control element. In particular, the present invention is an improvement in apparatus disclosed in the Satterlee Patents No. 2,131,759, issued October 4, 1938; No. 2,147,674, issued February 21, 1939; and No. 2,264,333, issued December 2, 1941.

In these prior systems a direct current motor is driven by means of alternating current source which is applied to the direct current motor through gaseous conduction tubes, known by the trade name as "Thyatron" tubes. Such tubes permit current to flow through them only in one direction so that by proper arrangement of the tubes current may be made to flow through the motor in either direction, depending upon which tube is being operated, thus providing a motor drive in the forward and reverse directions, depending upon which way the current flows through the motor. A separate coil is used in these cases for field excitation so that the direction of the flux or current in the field need not be changed for reversing the direction of rotation of the motor.

In Patent No. 2,264,333 a source of alternating potential adjustable in phase angle is impressed upon the control grid of the gaseous induction tube in such a manner as to shift the instant of discharge of the thyatron tube during the alternating current cycle.

In Patent No. 2,147,674 the biasing potential may be obtained either by a direct current generator or a potentiometer, or through a phase voltage obtained through a Selsyn generator.

In the present invention the control resides in the adjustment as desired of the potential applied to the grid of a discharge tube in combination with a steady pulse discharge applied on the same grid directly or indirectly.

The present invention is particularly adaptable for use in the operation of a motor both in a forward and reverse direction since the control cir-

cuit employed offers an efficient braking means for reversing the direction of rotation of the motor from one direction to the opposite direction.

A further advantage in this circuit is that after the reversal has been accomplished, the acceleration or deceleration of the motor in the desired direction is accomplished in the same manner for both forward and reverse rotations. These and other features provide acceleration and deceleration rapidly and over a wide range without hunting or overshooting and further effect adjustments under load conditions so rapidly that little or no variation in speed is experienced with variation of load. The circuit further is easily adjustable for operating conditions in such a way so that it may be changed to suit all demands or changes that the motor may be called upon to meet. Speed variation may be obtained from practically no speed to over-speed values for the motor.

Further advantages and merits of the present invention will be more clearly understood from the description in the specification below showing an embodiment of the invention when read in connection with the drawings in which Fig. 1 shows a circuit diagram for the system, and Fig. 2 shows two sets of curves *a* and *b* illustrating operating conditions for the system.

In the arrangement shown in Fig. 1, 1 indicates a direct current motor armature which is provided with a magnetic field by means of the field winding 2. In the arrangement of Fig. 1 the motor armature is connected to a gear reduction system 3 which operates the load 4 which may be any type of device, as, for instance, a radio locator, a submarine signal sounding ranging head, a turret gun, rotating machinery or positioning devices generally used for industrial purposes. The load 4 is tied in with a "Selsyn" system that is a self-synchronizing system 5 in which the portion 6 is intended to be used as the rotating element and the portion 7 as a stationary element. The stationary portion of the Selsyn 5 is tied in with a second Selsyn 8 which is provided with a rotor 9 adapted to be positioned through the reduction gear 10 operated by a manual control indicated by a handwheel 11. If desired, this system may be tied up with a gyro compass through the Selsyn unit 12 which is supplied by alternating current over the line 13.

which may be of any desired frequency, 60 cycles or more, the gyro compass will rotate the rotor element 14 and vary the phase impressed upon the Selsyns 5 and 8 so that the variation in voltage appearing across the rotor winding 9 which provides the signal impulse for the operation of the system will be the differential phase voltage between the Selsyns 5 and 8 or that existing as a resultant component among all three Selsyn units 5, 8 and 12 if the unit 12 is used. In this way it will be possible to provide, for instance, on shipboard, an absolute directional control for the turning of a directional pickup system as, for instance, a submarine signaling ranging unit or an electromagnetic directional ranging system.

The signal voltage applied across the rotor winding 9 is impressed between the cathode 15 and the grids 16 and 17 of the vacuum tube 18. This tube 18 is supplied between the cathode 15 and the anodes 19 and 20 with alternating potentials 180 degrees out of phase with each other through the transformer 21 which may be energized by the same alternating current potential applied to the Selsyn system.

The tube 18 may be of the 6N7 type and is, in fact, used in the circuit described as a rectifier. A resistance 22 may be used as a bias for the cathode and each anode-cathode circuit may be provided with similar resistances 23 and 24 which are connected in circuit with the vacuum tubes 25 and 26, respectively, to provide grid bias control for the motor circuits which will be described later. Since the grids 16 and 17 of the tube 18 are connected together, their potential is always the same and therefore unless the phase on the anodes 19 and 20 is ninety degrees out of phase with the grid voltage, the grid voltage can only be in the proper phase with one of the anode-cathode circuits of the tube 18. When it is in phase, therefore, with the anode-cathode circuit 15 and 19, an increased amount of current will flow through the resistor 23 in the direction of the arrow F; and when the grid potential is in phase with the anode-cathode circuit 20-15, an increased amount of current will flow through the resistor 24 in the direction of the arrow F'. Therefore, as the potential on the grid 27 of the tube 25 becomes more negative, the grid 28 of the tube 26 will become more positive and so, therefore, the tube 26 will tend to conduct increased current through the resistor 35 in the direction of the arrow G' while the current in the resistor 36 in the direction of the arrow G will drop to zero.

This system, therefore, provides opposite changes in two halves of a symmetrical circuit. The vacuum tubes 25 and 26 which may be of the same type as the vacuum tube 18 are energized through a direct current rectifier 29, the potential of which is applied between the cathodes 30 and 31 and the anodes 32 and 33 of the tubes. The positive potential of the rectifier 29 is not applied directly to the anodes 32 and 33 but through the resistors 35 and 36 which are connected in series across the anodes 32 and 33. The result of this arrangement is that when the signal voltage biases the cathode-anode current in one of the tubes 25 or 26 to a cut-off value, the potential from the point B to C is in one direction, and when the current in the other tube is biased to cut off, the direction of the potential drop reverses. In this change the potential across the appropriate resistor 35 or 36 becomes zero and therefore the potential of the appropriate anode

becomes that of the point A. The potential from the point B to C controls the voltage drop across a parallel resistance divider circuit made up of the resistances 37 and 38 which provide potentials entering as elements in the control of the grids 39 and 40 of the gaseous discharge tubes 41 and 42, respectively, which control the supply of current to the armature 1 of the motor in a manner which will be presently described.

The center point D between the resistances 37 and 38 is connected by an adjustable tap 43 to a potentiometer 44 which is connected in series with a fixed resistance 45 across a second rectifier 46 which may also be used to supply current to the field of the winding 2. The gaseous discharge tubes 41 and 42 have cathodes 47 and 48 which are connected to each other through resistances 49 and 50 of equal magnitude. The midpoint 0 between the resistance 49 and 50 is tied to one side of the rectifier 46 to which the resistance 45 is connected.

It will be noted that the points B' and C' are always at the same potentials as the points B and C, respectively, and it further should be noted that the currents flowing through the resistances 37 and 38 at any instant are always in the same direction. Therefore, as the potential B approaches the potential A through the cutoff of current in the resistance 38, the potential drop from B' to C' increases, tending by this action to decrease the negative bias on the grid 48 of the tube 42. Current may flow in either direction from B' to C'. If the current collapses in the resistance 36, current will flow through 38 and 37 in the direction from B' to C', while if current collapses in the resistance 35, current will flow in the opposite direction in the resistances 38, namely from C' to B'. A change in direction of the flow of current in the resistances 37 and 38 brings about a reversal of biases on the grids 39 and 40 and consequently the reversal of rotation of the armature 1. However, before a complete reversal occurs from one direction to the other, the current in the resistances 37 and 38 decreases in magnitude before reversing direction. This has the effect, as will be noted later, of decreasing the signal voltage below that of the generated back E. M. F. since this current decrease occurs with a more rapid acceleration than the decrease in armature speed, and therefore provides, as will be seen later, a reversal of current flow through the armature even before the direction of rotation of the motor is changed. This action, too, is sufficiently uniform and gradual so that a smooth transition is made from forward to reverse rotation. The rectifier 46 is connected between the cathodes 47 and 48 and the grids 39 and 40 so that a small negative bias may by this means be applied to the grids of the discharge tubes with respect to the cathodes. In the curves a and b of Fig. 2 this is indicated by the dotted lines K and K' labelled in both cases "potential applied for adjustment referred to '0,'" the potential being applied to the grids. This is usually a small value of the order of two or three volts. The potential drop applied between B' and C' in the operation of the system may vary over a great range, the range being from zero to the magnitude of the generated back E. M. F. or greater in either direction. When the tube 42 is firing during a portion of its positive half cycle, the voltage across from B' to D is such as to place a positive potential on the grid 40 of the tube 42. This is shown in the curve a of Fig. 2 as the dotted line L. Under these conditions the

potential drop through the resistance 58 will be such as to place the cathode 48 at a higher potential than the point O in the circuit. This is shown in curve *a* of Fig. 2 as the line M. The relative values between the signal D. C. on the grid and the back E. M. F. on the grid will vary, depending upon the instantaneous state of operation. If the signal voltage has suddenly been reduced, then the back E. M. F. may be greater than that of the signal volts. In the curve shown in *a* of Fig. 2, the instantaneous condition is that where the signal volts are higher than the back E. M. F. The net effect of this combination is to have a positive difference voltage of these two components on the grid 40 of the tube 42. Under these conditions the tube would fire unless the potential adjustment through the potentiometer 44 is such as to bring the negative bias on the grid 40 of the tube 42 below the critical voltage curve which is shown on *a* of Fig. 2 labelled "Critical grid voltage."

The discussion above does not take into consideration another important element in the grid control circuit. This is the condenser discharge circuit of which there are two, one 51 connected in series in the grid circuit 38 and one 52 connected in series in the grid circuit 40. These circuits are energized through selenium rectifiers 53 and 54 energized through the windings 55 and 56, respectively, through the alternating current source 57. The windings 55 and 56 are 180 degrees out of phase with each other so that the rectified impulses supplied across the resistances 57 and 58 are 180 degrees out of phase with each other. These rectified pulses supply a direct current pulse discharge in the grid circuits indicated by the curves N and N' and curves *a* and *b* of Fig. 2. The adjustment of this discharge circuit may be such as to provide always a small amount of negative bias through proper choice of values of resistance and capacities in the discharge circuit. The pulse, however, is such as to provide a rather rapid decrease in grid potential during the critical part of operation of the tube so that the instant of discharge of the tube may be readily controlled.

In the curve *a* shown in Fig. 2 the negative biases on the grid 40 of the tube 42 with respect to the cathode is the sum of the instantaneous values on the curve N, the line K and the line M while the positive potential on the grid is that of the line L. If the absolute values at a given instant of N, K and M are greater than L by an amount equal to the critical grid voltage value, then the tube 42 will not discharge.

The tubes 41 and 42 have their anode-cathode circuits connected in reverse direction through the armature 1 and the alternating current transformer windings 60 and 61 supplied through the supply line 57. These windings 60 and 61 are also 180 degrees out of phase with each other, the phase of 60 being the same as that of 55 and the phase of 61 being the same as that of 56. The alternating potential is shown in the curves *a* and *b* of Fig. 2 as P and Q, respectively, P being applied to winding 61 and Q to the winding 60.

It may be assumed for reference that current flowing through the tube 42 will ultimately bring about operation of the armature in the forward direction, and current flowing in the tube 41 will ultimately bring about operation in the reverse direction, the word "ultimately" being used in the sense that during the transition period, the motor may not be rotating in the direction corresponding to the flow of current in the tube.

The operation of the system will best be understood by assuming various practical conditions of operation. Assume, first, that it is desired to accelerate the rotation of the armature 1 in a forward direction. In this case the discharge tube 42 will, under our presumption previously made, be the tube to fire. To accomplish this the potential drop across the resistances B', C' must be in the direction from left to right in Fig. 1 and consequently the drop from B to C will be in the same direction. This means that the current flow in the resistance 36 must decrease and that in the resistance 35 increase. This is accomplished by biasing the grid 27 of the tube 32 to cut off the cathode-anode current flow which, in turn, is accomplished through increase of current through the resistance 23 in the direction of the arrow F. The phase and direction, therefore, of the potential in the grid 16 of the tube 18 is positive during the positive half cycle potential between the cathode 15 and the anode 19, thus causing current to flow through the resistance 23 in the direction of the arrow F. During this moment the current in the resistance 24 in the direction of the arrow F' has decreased, meaning that the bias is in such a direction that there is a tendency to decrease the current flow between the cathode 15 and the anode 20 in the tube 18.

Under conditions where the currents F and F' are equal which is when the grid bias is at a point midway between the two positive phases on the cathodes, the currents flowing in the resistances 35 and 36 will be in equal and opposite directions, which means that the potential between the points B' and C' will be zero and therefore no current will be flowing in the resistors 37 and 38.

When the anode-cathode current in the tube 25 is cut off, the potential at the point B' is greater than at C' and current flows through the resistors 38 and 37 from the left to the right as shown in Fig. 1. If, however, current is cut off in the anode-cathode circuit of the tube 26, current will flow in the resistance 36 and the potential of C' will be higher than the potential of B'. The reversal of direction of rotation of the motor is accomplished in this fashion. In between these points of extremity, the potential drop between B' and C' and therefore B' and D may be decreasing to such an extent that the tube 42 will not fire while the tube 41 will fire. In this case the back E. M. F. is greater than the signal voltage and as a result the tube 42 will cease discharging before the tube 41 commences to discharge because of the applied negative potential in the resistances 44 and 45. The resistances 44 and 45 in this change-over have current flowing in such a direction that they aid in maintaining the negative bias on the tube 41 and oppose the positive bias of the resistance 38 on the tube 42. As the current across the resistance from B' to C' decreases, the positive bias on the grid 40 will be overcome by the negative drop in the resistances 44 and 45 and the back E. M. F. drop in the resistance 50. Since the drop in the resistances 38 and 37 is equal, the bias applied to the grid 49 will be the sum of both negative potentials, namely that in the resistance 37 and the resistances 44 and 45, making a larger magnitude of negative bias applies to the grid 39 than positive bias applied to the grid 40.

Following, however, this point of operation, the back E. M. F.'s in the resistances 49 and 50 take over to create a sufficient bias on the tube 41 so that this tube will operate. This bias may be slightly less than zero, perhaps one or two volts, or

a little greater or equal to zero, in which case the tube 41 fires for the complete cycle. The term "positive bias" in the above discussion is used in the limited sense, that the direction of potential applied to the grid is positive through the element mentioned, but it may not, however, be absolutely positive because of the other negative components making up the absolute bias on the tubes. In this connection it will be noted that most discharge tubes will discharge for the complete positive half of the cycle when the bias on the grids is zero or perhaps even slightly less than zero and that if the biases on the grids are less than zero, the discharge will occur during some point in the positive half cycle of potential applied between the anode and the cathode of the tube, depending upon the parameters of the tube and voltages establishing the characteristic of the critical grid voltage curves.

In the curves shown in Fig. 2 the curves R illustrate the grid voltage curves with reference to the alternating current cycles applied between the cathode and anode of the tube. The pulse discharge produced across the resistances 57 and 58 creates a negative bias applied to the grids 39 and 40 of the tubes 41 and 42, which bias varies in accordance with the curves N and N' previously mentioned. The instantaneous magnitude of the potential supplied by these pulse discharges is a component which must be added algebraically to the other potentials applied to the grid to determine the instantaneous potential as applied to the grid with reference to the alternating cycle between the anode and cathode of the tube and the critical grid voltage characteristic. In normal conditions when the discharge tubes are not operating, this total potential on the grid is such as to place the pulse curve below the critical grid voltage line. In curve a of Fig. 2 it will be noted that the curve N in its full-line position intersects the critical grid voltage characteristic. It should be noted, however, that in this set of curves the impulse discharge on the grid is referred to the point O in the same way that the curves L, M and K are referred to the point O. The net bias voltage in these curves of Fig. a is such that the curve N with reference to the voltage across the anode-cathode of the tube would be dropped to the dotted line position of the curve N² and thus the tubes in this condition may not be firing. If, however, the signal voltage or preferably the voltage from B to C' is increased from the value L to the value of, say, L₁, the curve N may be raised to the point N³, bringing about the intersection between the critical grid volt curve and the curve N³ at such a point to bring discharges in the cycles shown in the shaded areas H. If this is assumed to be the discharge in the tube 42, the motor will be operated in the forward direction.

Referring now to the curves of b in Fig. 2; while the pulse in the curve a is in the position N², the pulse in the curves of b may be in the position N'. If the tube 42 is firing, no discharge will occur in the half cycles of the curve Q. If, however, the signal volts L' in curve b should suddenly decrease in magnitude, in curves b the line of the signal volts will change from a position L' to L'', thus in effect raising the impulse discharge curve to the dotted line position N² which intersect the critical grid volts curve to provide a discharge in the shaded area H'. In this condition the motor will be running in a forward direction but current will be passed through the motor in a reverse direction, thus

providing an effective brake action. The motor will reverse in the curves b of Figure 2 when both the back E. M. F. lines and the signal volts lines rise above the zero reference line and become positive potentials. In this case, of course, the lines M and L in curves a will pass below the zero reference line.

The resistances 70 and 71 in the grid circuits of the tubes 41 and 42 are current-limiting resistors. The adjustable tap on the potentiometer 44 is adjusted to such a point that with no potential across from B' to C', neither of the tubes 41 and 42 will discharge. The control of the torque characteristic on the motor 1 is obtained through the adjustment of values of the condensers 72 and 73 with the resistances 57 and 58, respectively providing the desired form for the discharge curves N and N'. In place of the rectifiers 29 and 46, direct current supplies may be used.

The system as a whole provides an infinite speed variation under any desired load conditions and both rapid acceleration and deceleration and also reversal of rotation with smooth accelerations and decelerations. If the motor is set for any given speed, a change in load will not substantially change the motor speed and any momentary slight change which may occur will be very rapidly restored.

As a follow-up system the arrangement has been used with an accuracy greater than one-tenth of a degree.

Having now described my invention, I claim:

1. A control circuit for operating a motor comprising a gaseous discharge tube having cathode, anode and grid electrodes and circuits, means for supplying the anode-cathode circuit with alternating potential and means for supplying a control potential to the grid-cathode circuit, said last means including a plurality of series-connected resistors between grid and cathode, a condenser connected in parallel with one of said resistors, means including a rectifying element for periodically charging said condenser solely from said alternating potential supply means, the charge consisting of a negative pulse occurring during each non-conductive half cycle of said gaseous discharge tube and gradually becoming less negative during each conducting half cycle thereof, whereby the pulse potential gradient is substantially uniformly inclined to the critical grid voltage line during said conductive half cycle, means for impressing across a second of said resistors a potential varying with motor speed, and means for impressing across a third of said resistors a control potential adjustable in magnitude.

2. A control circuit for operating a motor comprising a gaseous discharge tube having cathode, anode and grid electrodes and circuits, means for supplying the anode-cathode circuit with alternating potential and means for supplying a control potential to the grid-cathode circuit, said last means including a plurality of series-connected resistors between grid and cathode, a condenser connected in parallel with one of said resistors, means including a rectifying element for periodically charging said condenser solely from said alternating potential supply means, the charge consisting of a negative pulse occurring during each non-conductive half cycle of said gaseous discharge tube and gradually becoming less negative during each conducting half cycle thereof, whereby the pulse potential gradient is substantially uniformly inclined to the

critical grid voltage line during said conductive half cycle, means for impressing across a second of said resistors a potential proportional to the motor's back electromotive force, means for impressing across a third of said resistors a direct potential separately rectified from said alternating potential supply means and means for impressing across a fourth of said resistors a control potential adjustable in magnitude.
